UNITED STATES PATENT OFFICE

118,826

DESIGN FOR A CREAM REMOVER

J. Showles MacLean, Toledo, Ohio

Application October 4, 1939, Serial No. 87,511

Term of patent 14 years

To all whom it may concern:

Be it known that I, J. Showles MacLean, a subject of the King of Great Britain, residing at Toledo, in the county of Lucas and State of Ohio, have invented a new, original, and ornamental Design for a Cream Remover, of which the following is a specification, reference being had to the accompanying drawing, forming part thereof, and wherein Fig. 1 is a perspective view of a cream remover, showing my design; Fig. 2 is a side elevational view, the lower portion being shown in section; Fig. 3 is a top plan view; and Fig. 4 is a bottom plan view thereof.

I claim:

The ornamental design for a cream remover, as shown.

J. SHOWLES MACLEAN.
